UNITED STATES PATENT OFFICE.

JOHN A. SEELY, OF NEW YORK, N. Y.

GALVANIC BATTERY.

SPECIFICATION forming part of Letters Patent No. 369,034, dated August 30, 1887.

Application filed August 12, 1885. Serial No. 174,179. (No model.)

To all whom it may concern:

Be it known that I, JOHN A. SEELY, a citizen of the United States of America, residing in the city, county, and State of New York, 5 have made a new and useful Improvement in Galvanic Batteries, of which the following is a specification.

The object of my invention is, first, to provide an air-tight cover for battery-jars which 10 shall serve the purpose of preventing gases arising from the battery solutions within said jars from escaping therefrom, and to thus prevent said gases from attacking and destroying the electrical contacts by which electrical 15 conductors are connected with the battery elements.

The second object of my invention is to provide a carbon plate for galvanic batteries having a large surface exposed to the battery 20 solution in proportion to the volume of material employed in said plate.

Figure 1 represents a side view of my battery-jar in which the covering-cap is partially shown in section. Fig. 2 is a perspective view 25 showing the battery-cover and my improved carbon electrode, and also the various other parts of the battery.

A B is a cap having a downwardly-projecting flange and a plane top. The zinc electrode Z and the carbon electrode C project 30 upwardly through closely-fitting apertures in the top of the battery-cover, and the flange B of the said cover is pressed tightly over and around the top of the battery-jar, said jar being shown in the drawings in dotted lines. 35 The body of said battery-cover is preferably formed of two or three thicknesses of strong canvas or other suitable flexible fabric. This body is then covered upon its inner and outer 40 surfaces with soft india-rubber, which, after being applied to said canvas in the form of a paste or liquid, is vulcanized, but only to a degree to render the entire mass of said cover flexible. I find that nine thirty-seconds of an 45 inch (more or less) is a suitable thickness of rubber to be applied upon the canvas body of the cover. The canvas body of the cover A B thus provided with vulcanized india-rubber is made with apertures slightly smaller than

the cross sections of the upper ends of the battery elements. Such apertures afford a practically air-tight contact between the surfaces of the electrodes and the cover. The downwardly-projecting flange B of the cover, being secured with flexible india-rubber, may also 55 be sufficiently stretched to make a close contact with the upper edge of the glass jar, even when the horizontal cross-section of the jar considerably varies from a circle, as is shown in Fig. 2.

The upper extremity of the zinc element Z is provided with a set-screw, a, and an aperture, j, within which to thrust the end of a conducting-wire, while the lower end, k, of said zinc projects into the battery-fluid. The 65 carbon element C is provided with a series of deep grooves upon both of its sides, and said grooves are so formed that each has two inclined surfaces, d and m. Preferably at the bottom of said groove is a flat surface of considerable width. The top of each corrugation 70 may be of a narrow flat surface, or it may be formed by the angle of the two surfaces q and m. The upper portion, n, of the carbon element C has its projecting ridges removed, thus 75 leaving plane surfaces for contact with the walls of the apertures through the battery-cover.

b represents a suitable binding-post for connecting an electrical conductor with carbon 80 element C.

I am aware that others have heretofore constructed battery-plates with fluted corrugations, thus leaving very narrow spaces between adjoining flutes or ridges. My object, 85 however, in ridging the surfaces of the carbon element is to arrange the two opposite surfaces of each groove at a considerable distance apart, in order that a large amount of battery-fluid may be included between them, and to 90 thus avoid the excessive polarization in the battery-fluid, which would result if the facing surfaces of the grooves were very close together.

It is obvious that my battery-cover herein-before described is applicable not only to a galvanic carbon battery, but as well to all forms of batteries in which noxious gases arise 95

from the solution, and that it is also applicable to those batteries where a tight cover may be necessary for any purpose whatever.

What I claim, and desire to secure by Letters

5 Patent, is—

1. A battery-cover having a plane top, A, and a downwardly-projecting flange, B, formed of canvas and a flexible coating of vulcanized india-rubber.

10 2. A battery-cover having apertures for the battery elements Z C, having a plane top, A,

and flange B, said cover being formed of a body of canvas or other suitable material and a coating of soft vulcanized india-rubber.

3. A battery-cover having a top, A, and a 15 downwardly-projecting flange, B, formed of suitable flexible and elastic material, as and for the purpose described.

JOHN A. SEELY.
